(57) **CLAIM**

The ornamental design for a spatula, as shown and described.

DESCRIPTION

FIG. 1 is a front, left side perspective view of a spatula showing my new design;

FIG. 2 is a rear, right side perspective view thereof;

FIG. 3 is a front elevation view thereof;

FIG. 4 is a rear elevation view thereof;

FIG. 5 is a left side elevation view thereof, the right side elevation view being a mirror image of the left side elevation view;

FIG. 6 is an enlarged top plan view thereof; and,

FIG. 7 is an enlarged bottom plan view thereof.

The broken lines in the drawings illustrate portions of the spatula that form no part of the claimed design.
